UNITED STATES PATENT OFFICE.

THOMAS JOHANCEN AND EDWARD KEHOE, OF BALTIMORE, MARYLAND

TRUCK FOR HANDLING ROLLS OF PAPER.

Application filed December 27, 1922. Serial No. 609,278.

To all whom it may concern:

Be it known that we, THOMAS JOHANCEN and EDWARD KEHOE, citizens of the United States, residing at Baltimore, in the State of Maryland, have invented certain new and useful Improvements in Trucks for Handling Rolls of Paper, of which the following is a specification.

This invention relates to improvements in 10 tilting hand trucks and is directed particularly to a truck for handling rolls of print paper and moving them from one place to another such as to a place of storage or from the latter to a press.

15 Rolls of print paper are quite heavy and heretofore during their handling and movement from one place to another have been subject to damage when unloading and standing them upright on their ends. This 20 damage occurs when the rolls are tilted from a horizontal to a vertical position because their great weight has made it practically impossible, with the trucks employed, to lower the end onto a floor slowly and 25 without more or less of a drop. The weight being directed entirely on the rim edge of the roll causes the latter to burst from its outer side inwardly which frequently results in the damage of many pounds of paper 30 in each roll.

By means of our invention we are able to load the rolls onto the truck with facility and ease and afterward tilt the truck so the roll will be turned from a horizontal 35 to a vertical position gradually and with no shock or jolt that will cause damage so that a great saving of paper results.

The invention is illustrated in the accompanying drawing wherein,—

40 Fig. 1. shows the improved truck in top or plan view,

Fig. 2. illustrates the same in sectional side elevation.

45 Fig. 3. shows a vertical sectional view through the truck as the same would appear if cut on the line 3—3 of Fig. 2.

Fig. 4, illustrates certain parts of the truck in plan view as they would appear if viewed on the line 4—4 of Fig. 2, and

50 Fig. 5. shows an enlarged vertical sectional detail through the fluid-actuated control device to hold the tilting frame or table under control during the up-ending operation.

55 Referring to the drawings the numeral

10 designates a truck-frame, of structural metal with two spaced-apart horizontal upper bars 10¹ suitably braced to carry the load that is to be placed upon them, and said frame having two front wheels 11 and 60 a central rear caster wheel 12. This form of truck-frame is readily pushed about and turned because of the rear caster wheel.

The truck-frame carries two brake-levers 13 each of which is pivoted at 14 and the 65 outer end of each lever carries a brake-shoe 15, while the inner ends thereof are lapped and are pivotally connected by a single pivot-pin 16, to the forward end of a link-bar 17, as clearly shown in Fig. 1 of the 70 drawings.

The rear end of the link-bar 17, is pivotally connected to a brake-bar 18 which latter is pivotally attached at 19 to a bracket 20 on the frame so that its outer operating end 21 may project at the side of the truck.

This outer end 19 of the brake-bar passes through a side plate 22 on the frame which plate has a slot 23 with a depression 24 in 80 the forward end thereof so that when said lever-end 21 is pushed forward it will snap into said depression 24 and be held therein. When said lever-end is pushed forward into the depression the brake-shoes will be applied to the wheels.

The truck-frame 10 sustains a tilting frame or table 25 which, in this instance, comprises two side bars 26 of angle-iron shape which are rigidly connected by a series 90 of cross-bars 27.

The forward end of the table carries an inclined plate 28 to seat on the floor when the table is tilted.

The table is pivotally connected to the 95 truck-frame by means of a cross-bar 29 and by reference to Figs. 1 and 2 of the drawing it will be noted that this cross-bar pivot 29 of the truck-frame is located in a vertical plane to the rear of the vertical plane that 100 passes through the axis of the front wheels 11. By thus locating the pivot 29 we prevent the truck from tilting up at the rear when the forward end of the table is being lowered to the position shown in broken 105 lines in Fig. 2.

It will also be noted by reference to Figs. 1 and 2 of the drawing, that the table 25, when in the horizontal position seats on top of the horizontal upper bars 10¹ of the 110

truck-frame 10 and that the cross-bar 29 pivotally engages the side-bars 26 of the table at a point closer to the front than the rear ends thereof. The location of this 5 pivot closer to the front than the rear end of the table permits a slightly greater weight to be located at the rear of the pivot 29 and ensures that the table will not accidentally tilt downwardly at the forward 10 end while the truck is being moved from one place to another.

It is to be understood that the table is to be tilted by the operator lifting the slightly heavier rear end thereof so that the 15 tilting operation is entirely a manual one instead of being effected through power devices such as gears or levers. This fact enables the preliminary tilting movement to be effected quite rapidly and this movement 20 would increase in rapidity until the forward end of the table strikes the floor with a jolt were it not for means which we provide to avoid this.

A desirable and important feature of the 25 invention resides in the means employed to check the downward movement of the front end of the table during the operation of turning the heavy roll of paper from a horizontal to a vertical position, which means 30 will now be described.

The front axle 30 is provided with two spaced-apart depending brackets 31 which pivotally sustain a yoke-frame 32, the forward end 33 of which latter projects in 35 front of the axle and in a horizontal plane beneath the latter. This frame has a central bar 34 with an up-turned end 35 and the bar and frame may both swing on the pivot 36 at the rear end of the frame.

40 The up-turned end 35 of the bar 34 is pivotally connected to the lower head 37 of a cylinder 38 which latter normally extends upwardly in an inclined direction toward the forward end of the table 25.

45 The cylinder 38 has an upper head 39 and a stem 40 extends through this upper head and has its upper end pivotally engaged to one of the cross-bars 27 of the table by means of a sleeve 41, the connection of the stem 40 with the table being 50 at a point between the pivot 29 of the table and the forward end of the latter.

The lower end of the stem 40 passes 55 through the upper head 39 and into the cylinder 38 and this lower end of the stem engages a piston-head 42 on the interior of the cylinder, as clearly shown in Fig. 5.

The piston-head 42 has a cup-washer 43 which fits the cylinder wall and this washer 60 is provided with a plurality of openings 44 which register with openings 45 in the head above and below it. By means of these openings 44 and 45 passages are provided through the piston-head from the 65 upper to the lower side thereof.

Beneath the piston-head 42, there is provided a flexible disk or washer 46 which latter is held up against the bottom of the head by means of a metal washer 47 and the retaining nut 48, on the lower end of 70 the stem 40. The flexible disk or washer 46 will therefore cover the lower ends of the openings 44—45 when the piston-head is making a down-stroke.

By reference to Fig. 5, it will be noted 75 that a pipe 49 extends through the upper head 39 of the cylinder and communicates with the interior of the latter above the piston-head 42, and that said pipe extends down on the outside of the cylinder and has 80 its lower end attached to the lower head 37 at a passage 50 which passage communicates with the cylinder-chamber beneath the piston-head 42.

It is therefore to be understood that one 85 end of the pipe 49 enters the cylinder chamber above the piston-head while the other end of said pipe enters the cylinder-chamber below the said piston-head.

A valve 51 is located in the pipe 49 and 90 this valve enables the passages of fluid through the pipe to be restricted more or less as desired.

It is therefore to be understood that the 95 piston-head 42 and its stem 40 are attached to the table 25 while the cylinder 38 is sustained by the up-turned end of bar 34.

In operating the device we fill the cylinder 38 with oil or equivalent fluid and the valve 51 is then adjusted to cut-off or restrict the flow of the fluid through the pipe 49.

Presuming a roll of paper 52 (see broken lines in Figs. 1 and 2 and full lines in Fig. 3) to be lying horizontally on the table 25 105 in readiness to be deposited on the floor in an upright position.

The operator will place his foot on the end 21 of the break-lever and push the latter forward into the depression 24 thereby applying the shoes to the wheels to 110 prevent movement of the truck.

The rear end of the table 25 and the roll of paper thereon may then be lifted by one man as the pivot point 29 is so located as to enable one man to do this work.

As the rear end is thus lifted, the forward end of the table and roll will be lowered and during this lowering of the forward end there will first be a combined downward movement of the piston-head; the cylinder; the bar 35—34 and the front end 33 of the yoke-frame 32. This preliminary downward movement may be somewhat rapid.

As this preliminary downward movement is made the lower head 37 or the projection on the bottom thereof will seat on the floor, as shown in broken lines in Fig. 2 of the drawing and immediately the downward 130

movement will be arrested because the cylinder ceases to move and the piston-head 42 begins its travel downwardly in the cylinder.

As this further downward travel takes

5 place the oil in the cylinder beneath the piston-head 42, is driven out through the passage 50 and pipe 49 and through the valve 51 only as fast as said valve will permit the fluid to flow, which valve therefore

10 acts as a check and will permit the piston-head to move down only so fast as the oil can pass through the valve.

After the oil passes the valve 51 it is conveyed to the upper part of the cylinder

15 on top of the piston-head so that there is a circulation of oil from the under side of the piston-head to the upper side of the head and the piston can only move down as fast as that oil can be thus circulated.

20 This continues until the forward end of the table contacts with the floor whereupon the roll can readily be turned upright from the inclined position in which the tilted table has placed it.

25 After the roll has been stood upon its end the truck is withdrawn and the next operation is to return the table to the normal horizontal position. As no work is being accomplished during this return movement of the table, it is desirable that such movement be made rapidly and without requiring the oil on top of the piston to return slowly through the pipe 49 and valve 51 through which it was previously forced.

30 To permit this rapid return we use the flexible disk or washer 46.

When the oil or fluid is on top of the piston and it is desired to return the latter the rear end of the table 25 will be pulled down

40 which movement will draw the front end of the table up thus drawing the stem 40 from the cylinder. This movement is rapid because the oil that is on top of the piston will pass down through the openings 44-45

45 and spring the flexible disk or washer 46 downwardly as indicated by broken lines in Fig. 5, thereby allowing the oil to pass through the openings from the upper to the lower side of the piston-head without

50 requiring it to return through the restricted valve-opening in pipe 49. This makes the return movement of the table rapid.

Particular attention is invited to the fact that the cylinder and its piston are so connected between the truck-frame and the tilting table that the preliminary or first part of the table-movement from a horizontal to an inclined position causes the cylinder to also move without effecting a movement of

55 the piston 42 in said cylinder. This enables the preliminary movement to be more rapidly and readily made by the operator because he is not required to move the piston in the cylinder against the oil. When the cylinder however is brought to a stop as it is

when it seats on the floor, further movement of the table can only be made by moving the piston in the cylinder and displacing the oil therein which then acts as a brake in the final movement of the table.

70

By means of this invention heavy rolls of paper weighing hundreds of pounds may be readily up-ended without damage to or bursting of the rolls because the latter are lowered gently and under complete control 75 at all times until they are seated on the floor.

Having described our invention, we claim—

1. The combination with a truck-frame 80 having wheels thereon, of a tilting table pivotally attached to the truck-frame so as to swing from a horizontal to an inclined position, a cylinder to contain a fluid and having a piston therein said cylinder and piston being interposed between the truck-frame and the tilting table and movable together with the table while the latter makes a preliminary movement and upon a further movement of the table the piston and cylinder 85 being relatively moved to displace the fluid in the cylinder to check the movement of the table.

2. The combination with a truck-frame 90 mounted on wheels, of a table pivotally attached to the truck-frame so as to swing from a horizontal to an inclined position, a cylinder to contain a fluid, a piston in said cylinder said cylinder and piston being interposed between the truck-frame and the 95 tilting table and one of them having a connection with the truck while the other has a connection with the table and one of the said two connections being movable to allow the cylinder and piston to have a partial 100 movement with the table without changing the position of the piston in the cylinder as the table makes a part of its movement and said connections then operating to cause the fluid in the cylinder to be displaced by a 105 relative movement between the cylinder and its piston as the table makes its further movement.

3. The combination with a truck-frame 110 mounted on wheels, of a table pivotally attached to the truck-frame so as to swing from a horizontal to an inclined position, a cylinder to contain a fluid, a piston in said cylinder, a connection between the piston 115 and the table, a connection between the cylinder and truck said latter connection having a movement independent of the truck that will permit the cylinder and its piston to move together and without changing the relative relation of the one with respect to the other as the table makes a part of its movement and upon a further movement of the table to cause the piston to displace the fluid in the cylinder and be checked thereby.

4. The combination with a truck-frame 120

125

130

- 4
- mounted on wheels and having upper horizontal bars, of a table having spaced-apart side-bars which may seat upon the horizontal bars of the truck, means for pivotally connecting the bars of the truck with the bars of the table whereby the table may be swung from a horizontal to an inclined position with its forward end down, a cylinder having a piston said cylinder and piston being located between the truck and the table, 30 a rod attached to the piston and also connected to the table between the forward end of the latter and the pivot between the table and truck, a device pivotally connected to a portion of the truck and also pivotally attached to the cylinder whereby to permit the cylinder and its piston to be moved together downwardly by the forward end of the table as the latter makes a partial downward movement said device being arranged 40 so as to stop the downward movement of said cylinder and allow the piston therein to be moved downwardly as the forward end of said table continues its downward movement. 45
5. The combination with a truck-frame mounted on wheels and having upper horizontal bars, of a table having spaced-apart side-bars which may seat upon the horizontal bars of the truck, means for pivotally connecting the bars of the truck with the
- 10 15 20 25
- bars of the table whereby the table may be swung from a horizontal to an inclined position with its forward end down, a cylinder having a piston said cylinder and piston being located between the truck and the table, 30 a rod attached to the piston and also connected to the table between the forward end of the latter and the pivot between the table and truck, a device pivotally connected to a portion of the truck and also pivotally attached to the cylinder whereby to permit the cylinder and its piston to be moved together downwardly by the forward end of the table as the latter makes a partial downward movement said device being arranged 40 so as to stop the downward movement of said cylinder and allow the piston therein to be moved downwardly as the forward end of said table continues its downward movement. 45
- In testimony whereof we affix our signatures.

THOMAS JOHANCEN.
EDWARD KEHOE.
